JOSEPH DIX, OF ABBOTSFORD, WISCONSIN.

FLOOR-JACK.

SPECIFICATION forming part of Letters Patent No. 411,589, dated September 24, 1889.

Application filed August 9, 1888. Serial No. 282,349. (No model.)

To all whom it may concern:

Be it known that I, JOSEPH DIX, of Abbotsford, in the county of Clark and State of Wisconsin, have invented a new and Improved 5 Floor-Jack, of which the following is a full, clear, and exact description.

My invention relates to an improvement in floor-jacks, and has for its object to provide a simple, durable, and effective device 10 adapted for use in laying flooring and securing ceiling on the walls overhead or elsewhere; and the further object of the invention is to provide a device whereby the flooring or ceiling may be expeditiously and conveniently 15 jacked up and the device also quickly released from the said floor or ceiling when desired.

The invention consists in the construction and combination of the several parts, as will 20 be hereinafter fully set forth, and pointed out in the claims.

Reference is to be had to the accompanying drawings, forming a part of this specification, in which similar figures of reference indicate 25 corresponding parts in all the views.

Figure 1 is a plan view of the device. Fig. 2 is a section on line xx of Fig. 1, and Fig. 3 is an end elevation. Fig. 4 is a plan view of the body of the device. Fig. 5 is a perspective view of the jack-bar, shoe, and handle 30 detached from the body of the device. Fig. 6 is a perspective view of the shoe.

In carrying out the invention the body 10 is essentially rectangular in contour, and is 35 provided at its forward end with a downwardly-inclined nose 11, in the center of which nose at its outer end a concaved recess 12 is produced, adapted to facilitate the driving of the nails into the floor or ceiling 40 to be laid. The said forward end of the nose is also provided with a longitudinal groove 13, purposed to receive the tongue of the flooring.

Longitudinally and centrally of the body a 45 vertical essentially T-shaped slot 14 is formed, the horizontal member of the T being at the bottom of the body. The said T-shaped slot extends from the rear end of the body to a point approximating the nose, as

illustrated in Fig. 1. In the said slot 14 an 50 essentially T-shaped jack-bar 15 is arranged and adapted to slide, which bar projects, preferably, beyond its rear end, and is provided with a series of notches 16 at one side, adapted to receive a spring-actuated pawl 17, 55 pivoted upon the upper face of the body, as illustrated in Fig. 1. The pawl 17 is normally held in engagement with the notches 16 by a spring 17^a, secured to the body of the device at one end and bearing at the opposite end against the under side of said pawl.

Between the center of the body 10 and the nose 11 an elliptical or cam shaped rabbet 18 is produced, and immediately over the said 65 rabbet in the front end of the jack-bar a recess 19 is formed, in which recess a vertical roller 20 is journaled at or near the inner end of said recess. In front of the roller 20 a hook-shaped dog 21 is journaled, provided 70 with a cylindrical outer surface purposed to engage the walls of the rabbet 18.

Upon the upper surface of the dog 21 a shoe 22 is secured or cast integral therewith, which shoe upon its upper face is provided 75 with a transverse central recess 23. The dog and shoe are pivoted in the recess 19 of the jack-bar by means of a suitable spindle 24, passing through the said bar, dog, and shoe vertically, and upon the said spindle 24 is 80 also pivoted a handle 25, bearing upon the shoe 22 and extending outward through the recess 23 therein, as illustrated in Fig. 3.

In the forward wall of the rabbet 18, opposite the friction-roller 20, a second friction- 85 roller 26 is provided, journaled in a suitable horizontal opening produced in the nose 11. At or about the center of the jack-bar 15 a vertical spike or tooth 27 is projected downward at an inclination from the front rearward, as best illustrated in Fig. 2, which tooth or spike is loosely held in a suitable aperture in the jack-bar, and the lower end of the said spike is preferably beveled, as illustrated at 90 28, the bevel extending upward from the rear 95 in direction of the forward end or nose of the jack. At the rear of the central spike or tooth 27 a second spike or tooth 29 is simi-

larly fixed in the jack-bar, the two teeth being held normally in a fixed position through the medium of a spring 30, attached to said jack-bar and having its extremities upwardly 5 curved and engaging the contiguous faces of the spikes.

The spring 30 is purposed to prevent the teeth or spikes from dropping out when the device is inverted. The forward or cylindrical surface of the hook-shaped dog 21 is adapted to bear against the friction-roller 26, and the hub of both the said dog and attached shoe is purposed to have frictional contact with the opposite roller 20.

15 At one side of the rabbet 18 a second rabbet 31 is formed in the upper base of the body, as best shown in Fig. 1, the said rabbet 31 being adapted to accommodate the shoe 22 as the said shoe is revolved. The handle 25 is provided with a longitudinally-attached spring 32, one end of which spring passes down through the said handle at or near its pivotal point, being adapted to enter apertures 33, formed in the upper face of the 25 body at each side of the cam-rabbet 18.

In operation, the board adapted to be jacked having been placed in position, the device is laid upon the joist or other support for the said flooring, the groove 13 of the nose being 30 made to embrace the tongue of the board to be laid. The handle 25 is then carried fully over, or as far as possible to the left, as illustrated in Fig. 1, and either or both of the spikes or teeth 27 29 are driven into the joist 35 or equivalent support upon which the jack is rested. The handle is then grasped and carried to the right or toward the operator, whereupon, the cylindrical surface of the dog coming in frictional contact with the forward 40 wall of the cam-rabbet 18, the jack-bar, being locked, forces the body forward, exerting a strong and uniform pressure upon the flooring. When the desired pressure has been exerted upon the floor-board, the pawl 17, engaging with one of the notches 16 of the jack-bar, effectually holds the body steady and in close contact with the jacked timber. The 45 apertures 33 in the body may be made to surround the cam-rabbet 18, in which event the spring 32 of the handle will enter one of the said apertures and also serve to retain the device in the desired fixed position. By reason of the nose-recess 12, while the jack is still in position a nail may be readily driven into the board.

50 The slot 23 is formed in the dog-shoe 22 in order that if the handle should stop just where it is desired to drive the nail, without releasing the clutch of the jack upon the board, the handle may be shifted to one side 55 or to the other. The rollers in front and behind the dog and attached shoe enable the device to be easily manipulated. The flooring having been attached or nailed to the joist, the handle is again carried to the left, 60 which draws the body away from the flooring, whereupon the device may be readily

lifted and the spikes easily and conveniently disengaged.

Near the rear end of the jack-bar 15 a longitudinal slot 34 is provided, adapted to receive a brace-bar 35, which bar extends through the body from side to side, as best illustrated in Fig. 1, the said bar being purposed to strengthen the said body.

Having thus described my invention, what I 75 claim as new, and desire to secure by Letters Patent, is—

1. In a floor-jack, the combination, with a body provided with a nose at its forward end having a transverse groove, a central longitudinal essentially T-shaped slot, and a cam-rabbet produced in its upper face contiguous to the nose and intersecting the said slot, of an essentially T-shaped jack-bar having notches in one side and provided with a recess at its forward end, an essentially hook-shaped dog pivoted in the jack-bar engaging the walls of the cam-rabbet, a transversely-slotted shoe secured to the said dog, and a handle also pivoted to the jack-bar 85 vibrating in the recess of the shoe, detachable spikes passing through the said jack-bar, and a spring-actuated pawl engaging the notches of the bar, substantially as shown and described. 95

2. In a floor-jack, the combination, with a body having a nose integral with its forward end grooved transversely and provided with a recess in its upper face contiguous to the groove, a cam-recess formed in the upper face 100 of the said body contiguous to the nose, an essentially T-shaped jack-bar reciprocating longitudinally in said body, provided with notches in one face near its rear end and a recess in its forward end, and a spring-actuated pawl engaging the notches of the jack-bar, of an essentially hook-shaped dog pivoted in the forward end of the jack-bar 105 engaging the forward walls of the cam-rabbet, a transversely-recessed shoe secured to the 110 said dog, a handle vibrating in the recess of the said shoe, a friction-roller engaging the hub of the dog and shoe, and a second friction-roller engaging the outer cylindrical surface of the said dog, spikes loosely projected 115 through the jack-bar, and a spring engaging the contiguous surfaces of the spikes, substantially as shown and described.

3. In a floor-jack, the combination, with a body provided with a cam-rabbet in its upper face and a nose contiguous to the said cam-rabbet, provided with a transverse groove and an inclined central recess in its upper face contiguous to the groove, of an essentially T-shaped jack-bar sliding longitudinally in the body, having a recess in its forward end, an essentially hook-shaped dog pivoted to the jack-bar engaging the forward walls of the said rabbet, a shoe having a transverse recess fixed to the upper face 120 of the dog, a handle also pivoted to the jack-bar 125 vibrating in the recess of the shoe, fric-

tion-rollers engaging the front and rear of the said dog, spikes passing through the jack-bar at an inclination toward the rear, a spring engaging the contiguous faces of the 5 spikes, and a pawl pivoted to the upper face of the body engaging one face of the jack-bar at or near its rear end, all combined to operate substantially in the manner and for the purpose specified.

JOSEPH DIX.
